CLAIM

The ornamental design for a vehicle wheel, as shown and described.

DESCRIPTION

FIG. 1 is a front perspective view of the vehicle wheel;

FIG. 2 is a front elevation view thereof;

FIG. 3 is a rear elevation view thereof; and,

FIG. 4 is a left side elevation view thereof, the right side elevation view, top plan view, and bottom plan view being a mirror image thereof.

The broken lines shown in the drawings illustrate portions of the vehicle wheel that form no part of the claimed design.
